UNITED STATES PATENT OFFICE.

MAX HÄUSSLER, OF BERLIN, GERMANY.

FIRING DEVICE FOR BOILERS.

SPECIFICATION forming part of Letters Patent No. 600,673, dated March 15, 1898.

Application filed February 8, 1897. Serial No. 622,569. (No model.)

To all whom it may concern:

Be it known that I, MAX HÄUSSLER, a subject of the King of Prussia, German Emperor, and a resident of Berlin, in the Kingdom of 5 Prussia, German Empire, have invented certain new and useful Improvements in Firing Devices for Boilers and the Like, of which the following is an exact specification.

This invention refers in general to boilers 10 and to the furnaces of the same, and in particular to devices for firing coal-dust and for feeding the latter into the furnace.

The objects of my improvements are, first, 15 to avoid wasting the coal-dust, and, second, to obtain a better exhaustion of the heat resulting from the combustion of said coal-dust. I attain said objects, first, by making the coal-dust enter the furnace with such a velocity only as corresponds to the draft of the chimney, and, second, by forming the inner surfaces 20 of the walls of the furnace into concave shape and by rounding off the edges, corners, and angles of the flues of the boiler, so as thereby to prevent any precipitation of particles of ashes and the like. The precipitation 25 of coal-dust proper is nearly fully done away with by the means first mentioned. The particular feature of this means resides in the configuration of the tube leading the coal-dust from the distributing and driving or 30 feeding apparatus to and into the furnace, in that the diameter of said tube decreases in vertical direction and increases in horizontal direction from said apparatus to said furnace. In other words, the free section of the said 35 tube increases in the direction to the furnace, so that the speed of the mixture of coal-dust and air passing through the tube is correspondingly decreased, said decrease being 40 regulated so that the velocity of the coal-dust corresponds to the strength of the draft of the furnace, as aforementioned.

In order to make my invention more clear, I refer to the accompanying drawings, in which 45 similar letters denote similar parts throughout the different views, and in which—

Figure 1 is a diagrammatical view of a vertical longitudinal section through the boiler, the furnace, and the coal-dust distributing 50 and feeding apparatus. Fig. 2 is a vertical cross-section through the boiler, taken on lines 56 of Fig. 1. Fig. 3 is a plan of the coal-dust

distributing and feeding apparatus; and Fig. 4 is a vertical longitudinal section through the front portion of a boiler similar to Fig. 1, 55 the coal-dust-firing device being, however, dispensed with.

Referring to Figs. 1 and 2, the boiler shown is, as is seen, a Lancashire boiler, the heating-tubes a' of which connect the rear flue e^2 with a front flue e^3 . The flue e^2 corresponds 60 with the furnace e by the bottom flue e' , and the flue e^3 corresponds with the chimney (not shown) by the lateral flues e^4 e^5 , all as known with boilers of such type. 65

It is distinctly to be seen from Figs. 1 and 2 that the inner surfaces of the walls of the furnace e are formed into concave shape, and it is further to be seen that the same configuration is applied to the flues e' e^4 e^5 . Furthermore, the edges, corners, and angles of the flues e' e^4 e^5 , as well as of the flues e^2 e^3 , 70 are rounded off, so that obviously no precipitation whatever can take place.

Owing to the coal-dust being fed into the 75 furnace e with a speed corresponding to the draft of the chimney, the combustion of the coal-dust is of course more perfect than if the speed of the air driven into the furnace exceeds the strength of the chimney-draft. 80 Thus in consequence of said more perfect combustion the heat developed is correspondingly greater. In order to cause said heat to pass over more to the boiler proper than to the masonry of the same, I prefer to arrange heat-isolating plates i within said masonry in close 85 proximity to the flues.

The front portion of the bottom flue e' forms an incline which extends down to the rear end of the grate o . Between said rear end of the 90 grate and the lower front end of said bottom flue is left a small space, which generally is closed by a hinged plate u . The space mentioned is kept open as long as the boiler is fired with coal-dust, so that the slag accumulating upon said inclined portion of the bottom flue e' can flow down into the ash-pit r of the furnace. 95

The purpose of providing the furnace with a special grate in spite of firing the boiler 100 with coal-dust resides in the apparatus for distributing and driving, the coal-dust being as long unable to perform its function, as there is no steam for driving said apparatus

itself. Therefore the boiler is first fired with any suitable sort of coal burned in ordinary manner upon the grate *o*. As soon, however, as the steam produced has reached a tension sufficient for driving the coal-dust distributing and feeding apparatus this latter is caused to come into operation, when the grate *o* is not charged any further with the ordinary coal. The furnace is then fed with the coal-dust only, and the hinged plate *u*, which up to then was of course closed, is opened, so as to allow of the slag flowing down into the ash-pit *r*, as aforementioned.

The coal-dust distributing and feeding apparatus consists of the hopper *s*, the conveying-screw *x*, delivering the coal-dust from said hopper into the pipe *z*, and the tube *m*, communicating with the pipe *z* and having at its outer end a blower *w* for driving air into it and terminating with its other end into the furnace *e*, said other end having an inclined position and being directed to the inclined front portion of the bottom flue *e'*, as distinctly shown in Fig. 1.

In order to hinder the tube *m* from forming an obstacle for the fireman on attending the furnace, the portion *m'* of the tube *m* is vertically cranked for such a height that the fireman need not bend or bow on passing through below said portion *m'*. The portion *m'* is that which increases in breadth or width in the direction to the furnace, said increase being so measured that also the free section of the portion *m'* of the tube *m* increases, so that the speed of the coal-dust is correspondingly decreased, as already mentioned.

Another particular feature of the coal-dust distributing and feeding apparatus resides in the arrangement of a number of superposed horizontal pliable plates or bands *b*, which are arranged in steps below the termination of the pipe *z*. The coal-dust falling upon said bands causes these latter to oscillate, and a similar result is brought about by the air that is driven by the blower *w* into the

pipe *m* through the spaces between said bands *b*. The constant oscillations of the bands *b* are of very useful effect for the distribution of the coal-dust, which latter then, after thus being distributed, is carried away by the air. 50

Having thus fully described the nature of this invention, what I desire to secure by Letters Patent of the United States is—

1. The combination with a boiler, of a furnace having a grate and having the inner surface of its walls concave; a flue extending below the boiler proper, and forming in its front portion an incline extending down to the rear end of said grate; a hinged plate arranged between said rear end of the grate and the 55 lower front end of said flue; an inclined slot arranged within the wall portion above the grate, and being directed toward the inclined lower wall of the flue, and means for driving coal-dust through said slot into the furnace, 60 as set forth.

2. The combination with a boiler, of a furnace having a grate, and having the inner surfaces of its walls formed into concave shape; a coal-dust distributing and driving apparatus arranged outside the boiler; a tube connecting said apparatus with said furnace and decreasing in vertical and increasing in horizontal diameter toward said furnace; a pipe arranged about rectangularly to said tube 70 and terminating from above into the same and adapted to lead the coal-dust into the tube; a series of superposed pliable bands *d* arranged below the termination of said pipe in some distance one from the other, and 75 means for driving air through the spaces between said bands, for the purpose set forth.

In testimony whereof I have signed this specification in the presence of two subscribing witnesses.

MAX HÄUSSLER.
